William L. Symons
Atty.

UNITED STATES PATENT OFFICE.

GLEE BEUG, OF STURGIS, SOUTH DAKOTA.

DESIGN FOR A DOLL.

61,130.

Specification for Design. Patented June 27, 1922.

Application filed February 27, 1922. Serial No. 905. Term of patent 14 years.

To all whom it may concern:

Be it known that I, GLEE BEUG, a citizen of the United States, residing at Sturgis, in the county of Meade and State of South Dakota, have invented a new, original, and ornamental Design for Dolls, of which the following is a specification, reference being had to the accompanying drawings, forming part hereof, in which—

I claim:

The ornamental design for a doll, as shown.

GLEE BEUG.
